DESIGN FOR A COMBINED WINDOW SHADE BRACKET AND GUIDE

Edward A. Littman, Cudahy, Wis.

Application August 11, 1944, Serial No. 114,843

Term of patent 3½ years

(Cl. D21—1)

To all whom it may concern:

Be it known that I, Edward A. Littman, a citizen of the United States, residing at Cudahy, in the county of Milwaukee and State of Wisconsin, have invented a new, original, and ornamental Design for Combined Window Shade Brackets and Guides, of which the following is a specification, reference being had to the accompanying drawing, forming part thereof.

Fig. 1 is a front view of a combined window shade bracket and guide, showing my new design;

Fig. 2 is a side elevational view;

Fig. 3 is a top plan view; and

Fig. 4 is a perspective view thereof.

I claim:

The ornamental design for a combined window shade bracket and guide, as shown.

EDWARD A. LITTMAN.
